UNITED STATES PATENT OFFICE.

LEVI W. HORTING, OF LANCASTER, PENNSYLVANIA, ASSIGNOR OF ONE-THIRD TO CHARLES F. STAUFFER AND ONE-THIRD TO B. GRANT STAUFFER, OF LANCASTER, PENNSYLVANIA.

CENTRIFUGAL CUT-OUT.

1,135,801.

Specification of Letters Patent.

Patented Apr. 13, 1915.

Application filed January 10, 1913. Serial No. 741,290.

To all whom it may concern:

Be it known that I, LEVI W. HORTING, a citizen of the United States, residing at Lancaster, in the county of Lancaster and State of Pennsylvania, have invented certain new and useful Improvements in Centrifugal Cut-Outs; and I do hereby declare the following to be a full, clear, and exact description of the invention, such as will enable others skilled in the art to which it appertains to make and use the same.

This invention relates to centrifugal cut-outs particularly designed for use on that class of single phase alternating current rotors which are started by phase displacement and wherein the auxiliary starting coil or winding must be cut out after starting.

The cutout of the present invention may also be utilized to advantage elsewhere for automatically opening an electric circuit when a predetermined speed of a rotor is reached.

The most common cutout of this kind utilizes the centrifugal force developed by the revolving member for opening the circuit. As ordinarily applied, contact members or brushes are yieldingly mounted on the revolving member or rotor and are held by springs in sliding contact with stationary collector rings which are in the electrical circuit of the starting winding. After the revolving member reaches a certain speed the centrifugal force overcomes the force of the springs and the brushes are thrown out away from the collector rings, thus opening or breaking the starting circuit. Inversely, when the revolving member slows down to a speed where the centrifugal force exerted on the brushes is less than that exerted by the springs, the brushes move into engagement with the collector rings again, and the starting circuit is closed.

A cutout constructed as just described is subject to considerable wear from arcing and also from friction of the brushes against the collector rings.

It is the object of this invention to substantially reduce the arcing and frictional wear, and to this end to accelerate the movement of the brushes away from the collector rings when the cut out occurs, to distribute the frictional wear over an extended surface of the brushes, to provide a tension for the

brushes which is independent of the tension acting against the centrifugal force, and to make the cut out point on the brushes different from the starting point thereon, that is to say the point on the brushes which engages the collector rings when the cut out takes place different from the point on said brushes which is in contact with said rings at the start, thus protecting the contact at the start from any blistering that may occur when the circuit is broken.

The invention will be first hereinafter described in connection with the accompanying drawings, which constitute a part of this specification, and then defined with more particularity in the claims at the end of the description.

In the drawings, in which the same reference characters are used to indicate similar parts throughout; Figure 1 is a side view of the rotor of an induction motor to which a cutout embodying this invention is applied, only a fragment of the motor casing for supporting the collector rings being shown; Fig. 2 is a section taken on the line 2-2 of Fig. 1, showing the rotor in end elevation with the brushes in the position they occupy at the start; Figs. 3 and 4 are similar views, illustrating the respective positions of the brushes just before and after the cut out occurs.

Referring to Figs. 1 to 4 inclusive of the drawings, A designates the laminated body of the rotor and a its shaft. To one end of said body, and insulated from it, there is secured a bracket B having a post b on which is pivoted a lever C. On the free end of said lever the brushes c and c¹ are pivoted by means of a pin or rivet c². The two brushes are separated from the body of the lever by bosses c³ and c⁴ around which are mounted helical springs c⁵ and c⁶ which by acting between the lever and the brushes tend to move the latter in the direction indicated by the arrow c⁷ in Figs. 2 and 3. Said brushes have projections or tails c⁸ and c⁹, respectively, extending at the opposite side of the pivot pin from their heads or friction ends and balancing the latter ends. The bracket B also has other posts or projections b¹ and b² which act as stops to limit the movement of the lever C and the tails of the brushes as will be hereinafter explained. Still another post or projection b³

is mounted on the bracket, this one being provided for the attachment of one end of a tension spring b^4 , the other end of which is connected to the lever C. Said spring tends to hold the lever against the inner stop b^1 .

A fragment of the motor casing or stator is indicated at D and is provided with a collar or sleeve d around the shaft a of the 10 rotor. The collector rings d^1 and d^2 are mounted on this sleeve or collar and are insulated from each other and from the casing. The brushes are held in contact with the respective collector rings by the springs 15 c^5 and c^6 when the rotor is at rest and until it reaches the predetermined speed at which the cut out is designed to occur.

In operation, as the rotor gathers momentum after starting, centrifugal force throws 20 the lever C outward against the tension of the spring b^4 , so that said lever moves away from the stop b^1 and in the direction of the stop b^2 . The springs c^5 and c^6 , however, keep the heads of the brushes in contact 25 with the collector rings independent of the tension of the spring b^4 at a minimum pressure until the tails of said brushes come in contact with the stop b^2 . Further outward movement of the lever under the influence 30 of the increasing centrifugal force will then cause the heads of the brushes to be quickly moved out away from said rings by reason of the fact that the distance from the pivot pin c^2 to the fulcrums of the tails against the 35 stop b^2 is very much shorter than the distance from said pivot pin to the contact points of the heads of the brushes upon the rings. It will thus be seen that the cut out does not take place until the predetermined 40 speed of the rotor is reached, and when it does occur, the movement of the brushes away from the collector rings is accelerated to such an extent, as compared with previous devices of this kind, that arcing is greatly 45 reduced.

During the outward movement of the lever C, the point of contact of the brushes upon the collector rings shifts from that shown in Fig. 2 to that shown in Fig. 3 where the 50 cut out is just about to be effected. Consequently, the frictional wear on the brushes will be distributed along this extended contact space instead of being concentrated at one point as in previous constructions. Not 55 only is the frictional wear very much reduced by this improved device, but it has the further advantage of making the cut out contact point of the brushes upon the collector rings different and well removed from the starting contact point of said brushes, whereby the contact at the start is protected 60 from any blistering that may occur when the circuit is broken. The cut out point is placed at the extremity of the contact space of the brushes which is farthest removed

from the pivot pin c^2 , thus lengthening the head end or lever arm of the brushes as compared with the tail end or lever arm thereof, and increasing the rapidity of action of the cutout so that it operates almost instantaneously. At the same time, the tails of the 70 brushes balance the heads thereof, so that the only tension on said brushes is that of the springs c^5 and c^6 which act independently of the spring b^4 that opposes the centrifugal force. 75

It should be understood that this invention is not limited to the details of construction herein illustrated and described, but is only restricted to the essential structural 80 features and combinations of parts specified in the appended claims.

Having thus described my invention what I claim as new and desire to secure by Letters Patent of the United States is: 85

1. A centrifugal starting switch for electric motors including in combination a fixed contact, a movable contact mounted on a movable pivot arranged intermediate of the ends of said movable contact, resilient means for normally keeping the movable contact in engagement with the fixed contact while the pivot is moved outward to a certain point by centrifugal force, and a stop adapted to engage the tail end of the movable contact when said certain point is reached in the outward movement of said pivot, said stop serving as a fulcrum for removing the head end of said movable contact from the fixed contact as the pivot of said movable contact is thrown farther out by increasing centrifugal force. 95

2. A centrifugal starting switch for electric motors including in combination a fixed contact, a movable contact mounted on a movable pivot arranged intermediate of the ends of said movable contact, resilient means for normally keeping the movable contact in engagement with the fixed contact while the pivot is moved outward to a certain point by 100 centrifugal force, and a stop adapted to engage the tail end of the movable contact when said certain point is reached in the outward movement of said pivot, said stop serving as a fulcrum for removing the head 105 end of said movable contact from the fixed contact as the pivot of said movable contact is thrown farther out by increasing centrifugal force, the stop engaging point on the tail end of said movable contact being much nearer the pivot thereof than the point on the tail end of said movable contact which engages the fixed contact just before said contacts are separated. 110

3. The combination in a centrifugal starting switch, of a stationary and a rotatable member, a contact on said stationary member, an arm pivoted on said rotatable member, stops at either side of the free end of said arm, resilient means tending to hold 115

said arm against the inner stop, a movable contact pivoted intermediate of its ends on the free end of said arm, and resilient means for holding the head end of said movable contact in engagement with the fixed contact while the pivot of the movable contact is moved outward by centrifugal force, against the influence of said resilient means acting on the arm, until the tail end of said movable contact engages the outer stop, whereupon further outward movement of said pivot due to increasing centrifugal force will cause the head end of the movable contact to be removed from the fixed contact.

4. The combination in a centrifugal starting switch, of a stationary and a rotatable member, a contact on said stationary member, an arm pivoted on said rotatable member, stops at either side of the free end 20 of said arm, resilient means tending to hold said arm against the inner stop, a movable contact pivoted intermediate of its ends on the free end of said arm, and resilient means for holding the head end of said movable contact in engagement with the fixed contact while the pivot of the movable contact is moved outward by centrifugal force, against the influence of said resilient means acting on the arm, until the tail end of said movable contact engages the outer stop, whereupon further outward movement of said pivot due to increasing centrifugal force will cause the head end of the movable contact to be removed from the fixed contact,

35 the point on the tail end of said movable contact engaged by said outer stop being much nearer the movable pivot than the point of the head end which engages the fixed contact just before said contacts are

40 separated.

5. The combination with stationary collector rings insulated from each other, a rotor, brushes carried thereby and mounted on a movable pivot arranged intermediate 45 of their ends, resilient means for holding the head ends of said brushes in engagement with the respective collector rings while the pivot is moved outward to a certain point by centrifugal force, and a stop adapted to engage the tail ends of the brushes when said certain point is reached in the outward movement of said pivot, said stop serving as a fulcrum for removing the head ends of the brushes from the collector rings as the pivot 50 of said brushes is thrown farther out by increasing centrifugal force.

6. The combination with stationary collector rings insulated from each other, a rotor, brushes carried thereby and mounted 60 on a movable pivot arranged intermediate of their ends, resilient means for holding the head ends of said brushes in engagement with the respective collector rings while the pivot is moved outward to a certain point by centrifugal force, and a stop on the rotor

adapted to engage the tail ends of the brushes when said certain point is reached in the outward movement of said pivot, said stop serving as a fulcrum for removing the head ends of the brushes from the collector 70 rings as the pivot of said brushes is thrown farther out by increasing centrifugal force, the points on the tail ends of the brushes engaged by the stop being much nearer the movable pivots than the points on the head ends of said brushes which engage the collector rings just before the cut out occurs.

7. The combination with stationary collector rings insulated from each other, a rotor, an arm pivoted thereon, stops at 80 either side of the free end of said arm, resilient means tending to hold said arm against the inner stop, brushes pivoted intermediate of their ends to the free end of said arm, and resilient means for holding the head ends of said brushes in engagement with the respective collector rings while the pivots of said brushes are moved outward by centrifugal force, against the influence of said resilient means acting on the arm, 85 until the tail ends of the brushes engage the outer stop, whereupon further outward movement of said pivots due to increasing centrifugal force will cause the head ends of the brushes to separate from the collector 90 rings.

8. The combination with stationary collector rings insulated from each other, a rotor, an arm pivoted thereon, stops at either side of the free end of said arm, resilient 100 means tending to hold said arm against the inner stop, brushes pivoted intermediate of their ends to the free end of said arm, and resilient means for holding the head ends of said brushes in engagement with the respective collector rings while the pivots of said brushes are moved outward by centrifugal force, against the influence of said resilient means acting on the arm, until the tail ends of the brushes engage the outer stop, whereupon further outward movement of said pivots due to increasing centrifugal force 105 will cause the head ends of the brushes to separate from the collector rings, the points on the tail ends of said brushes engaged by the outer stop being much nearer the movable pivots than the points on the head ends of said brushes which engage the collector rings just before the cut out occurs.

9. In a centrifugal starting switch a 120 swinging lever carrying a brush at its free end which is pivoted thereto intermediate its ends, resilient means tending to throw the lever in an opposite direction to the action of centrifugal force exerted thereon, other resilient means tending to hold the contact point of the brush in engagement with a fixed contact, a stop adapted to engage said brush between its pivotal point and the pivot of the lever and throw the contact 125 130 135

point of the brush out of engagement with said fixed contact as the lever is thrown by centrifugal force toward said stop.

10. In a centrifugal starting switch a swinging lever carrying brushes at its free end which are pivoted thereto, intermediate their ends, resilient means tending to throw the lever in an opposite direction to the action of centrifugal force exerted thereon, other resilient means tending to hold the contact points of the brushes in engagement with fixed contacts, a stop arranged near the pivotal point of the brush adapted to en-

gage said brushes between the pivotal points thereof and the pivot of the lever and throw 15 the contact points of the brushes out of engagement with said fixed contacts as the lever is thrown by centrifugal force toward said stop.

In testimony whereof I affix my signature 20 in the presence of two witnesses.
